ONE-MAN TORPEDO BOAT

Norman G. Baker, Laredo, Tex.

Application May 7, 1942, Serial No. 442,071

19 Claims. (Cl. 114—18)

This invention is a novel one-man torpedo boat in the nature of a small self-propelled vessel slightly longer than a standard torpedo and having one, two, three or more torpedo tubes disposed in its bottom and arranged in parallel relation, and having a pilot's compartment disposed above the torpedo tubes, said compartment being of low height and dome-shaped so that the pilot may operate and navigate the vessel while lying therein in a prone position, the vessel being normally submerged except for the upper portion of its dome-shaped top, thereby giving the vessel while floating or proceeding slowly the appearance of a floating log or other inoffensive object, the pilot's compartment containing in conveniently disposed locations the various controls for propelling and steering the vessel, and for releasing the torpedoes from the tubes after the vessel has first been aligned with the object towards which the torpedoes are to be launched.

Another object of the invention is to provide a one-man torpedo boat of the above type which may be readily carried upon and launched from relatively larger ships or boats, or can be carried upon and launched from speed boats owing to its relatively light weight, the pilot being first positioned in the pilot's compartment so that after launching he may then propel and steer the vessel within its cruising range into a desired area or position to lay in wait for approaching enemy vessels. When the enemy ships approach, the pilot can then maneuver the torpedo boat in an unsuspected manner close to their path, and the pilot will point the torpedo boat in the desired direction of travel of the torpedoes; and by actuating controls from the pilot's compartment, he may then release one or all of the torpedoes which, propelled by their own power and their rudders being previously set for a straight ahead course, will then proceed at relatively short range to strike their targets and thereby disable or sink the enemy ships.

A further object of the invention is to provide a one-man torpedo boat of the above type, wherein after one or more of the torpedoes have been released the pilot may operate suitable controls to restore the ballast or trim and degree of submergence of the boat to offset the loss in weight of the released torpedo, this being effected by admitting sea water into the port or starboard ballast tank, or by blowing water out of the starboard or port ballast tank, or by merely blowing water from one tank into the other.

A still further object of the invention is to pro-

vide a one-man torpedo boat of the above type which can proceed unsuspectingly under its own power towards, or lurk in the path of, enemy vessels for the purpose of more accurately launching torpedoes at close range; also the shallow draft of the boat renders it adaptable for slipping unsuspectingly into harbors, over nets and above sunken mines; and when the torpedoes have been released the boat may return under its own power to its mother ship, the entire operation of the boat requiring the services of only one pilot.

Another object of my invention is to approach within close range, thus insuring more accuracy in firing, shorter travel of the torpedoes which reduces cost and size of torpedoes of equal destructive powers.

A still further object of the invention is to provide a small light one-man torpedo boat of the above type in which construction costs are a minimum and which may be built or assembled quickly; also one having a low operating cost, and one that may be readily transported, and which obviates the use of more complicated accessories such as internal combustion engines, or heavy batteries; and also one which can be built in small shops not otherwise equipped for defense work.

I will explain the invention with reference to the accompanying drawings which illustrate one practical embodiment thereof, to enable others familiar with the art to adopt and use the same; and will summarize in the claims, the novel features of construction, and novel combinations of parts, for which protection is desired.

In said drawings:

Fig. 1 is a longitudinal section through the vessel taken mainly on the axis of one of the torpedo tubes.

Fig. 2 is a horizontal section above the floor level of the pilot's compartment showing the various controls.

Fig. 3 is an enlarged front elevation of the vessel.

Fig. 4 is a reduced rear end view thereof.

Fig. 5 is a vertical section on the line 5—5, Fig. 2.

Fig. 6 is a small diagrammatic perspective view of a modified torpedo boat carrying four torpedo tubes.

As shown, my novel one-man torpedo boat comprises a lower combined tank and torpedo tube section, of length somewhat greater than the overall length of a standard torpedo T, and of width sufficient to house one, two, three or more torpedo tubes I in parallel relation and spaced slightly apart, said tubes I being of di-

ameter slightly larger than the major diameter of the torpedoes T, so that the torpedoes may be readily slid into place in the tubes and housed therein with the ends of the torpedoes terminating within the ends of the tubes.

Connecting the parallel tubes 1 at their upper peripheries is a plate 2 forming the main floor or deck of the boat, said plate 2 being secured preferably by welding or otherwise to the tubes 1 in a watertight manner for reasons hereinafter stated. A bottom plate 3 is welded or otherwise secured to the lower peripheries of the parallel tubes 1 in a watertight manner, plate 3 being of somewhat greater width than plate 2. Side plates 4 are welded to the outer edges of the plates 2 and 3 at each side of the boat, plates 4 being spaced from the outer peripheries of the tubes 1. A horizontal division plate 5 is secured by welding or otherwise to the adjacent inner peripheries of the tubes 1 in a watertight manner, dividing the space between said tubes into upper and lower compartments.

The front end of the boat is bluntly pointed, and converging front plates 6, 6, connect the front edges of the plates 2, 3 and 4 with their meeting edges welded or otherwise secured together on the longitudinal axis of the boat, said plates 6, 6, being also welded or otherwise secured to the front ends of tubes 1, 1, in a watertight manner. At the rear end of the boat is a rear plate 7 welded or otherwise secured to the ends of the plates 2, 3 and 4, and to the ends of the tubes 1, 1.

The above construction provides a lower tank and a torpedo tube section of the hull in which the parts are secured together in a rigid manner, and in which the tubes 1, which may be one, two, three or more in number, extend entirely through the hull from end to end while the space within the hull section exteriorly of the tubes is divided into four tanks, i. e., two symmetrical outer tanks A and B respectively formed between the outer peripheries of the tubes 1 and the plates 2, 3 and 4; and two symmetrical inner tanks C and D, the upper tank C being disposed between the plates 2 and 5 and the upper inner peripheries of the torpedo tubes 1, the lower tank D being formed between the plates 5 and 3 and the lower inner peripheries of the tubes 1, as shown more particularly in Fig. 5. Tank C may hold fuel oil for the boiler burner, while tank D may hold a supply of fresh water for the boiler and for drinking or other purposes. The outer tanks A and B are ballast tanks for holding sea water to maintain trim or ballast and the degree of partial submergence of the boat, as hereinafter explained.

The torpedoes T are inserted in their respective tubes 1 from the front ends, and are slipped rearwardly into the tubes, the same being held in alignment by means of spaced lugs 1a (Figs. 1 and 4) which straddle the edges of the torpedo fins T', other lugs 1b being adapted to abut against the rear ends of the fins T' to limit the rearward movement of the torpedoes in the tubes. When so positioned with respect to the lugs 1a, 1b the torpedoes are held in position in the tubes by means of hold-down screws 8 adjacent the front ends of the torpedo tubes, which screws pass downwardly through stuffing boxes 9 in the floor plate 2 of the boat, the screws 8 being actuated by handwheels 10 so that the screws will depress the front ends of the torpedoes down in their respective tubes and prevent the torpedoes from

moving forwardly out of their tubes owing to the curvature of the forward ends of the torpedoes, as shown in Fig. 1.

The torpedo propelling devices are readily controlled by screws 11 having headed lower ends engaging the automatic actuating members carried by the respective torpedoes, said screws 11 passing downwardly through stuffing boxes 12 in the floor plate 2, and being operated by handwheels 13 or the like. By the above construction, when it is desired to release a torpedo from its tube, it is merely necessary for the pilot to first back the related hold-down screw 8 above the periphery of the tube 1, and then manipulate the handwheel 13 to set in action the propelling mechanism of said torpedo and simultaneously back the screw 11 above the periphery of the tube 1, whereupon the released torpedo will move forwardly out of the tube 1 under its own power, the torpedo being already immersed in sea water by reason of the fact that each end of tube 1 is open to the sea at the ends of the boat; and if the boat has been pointed in the right direction the torpedo will proceed in such direction directly at the desired target, its propeller having been set for straight-away course before the torpedo was placed in the tube. The member 11 however need not be a screw but may be any desired type of turning, pushing or pulling device conveniently located which will set in motion the propelling mechanism or turbine of the torpedo. A dial or gauge on the instrument board in the front of the pilot's compartment constitutes the torpedo aiming means, the pilot aiming the entire boat in the direction of the desired target. Therefore, the steering devices on the torpedo can be set for a "straight" course, and only the propelling devices of the torpedo need be set in motion when "firing." Means for preventing accidental discharge of the torpedo due to contact of its tip with an obstruction, such as a floating log, before its release from the torpedo, will be hereinafter described.

Above the tank and torpedo tube section of the hull is a narrow pilot's compartment disposed between the floor plate 2 and a semi-cylindrical hood 14, which latter may be made of thin metal and welded or otherwise secured to the upper edges of the lower hull section in a watertight manner due to the fact that the pilot's compartment is normally partially submerged below the sea level.

The pilot's compartment extends substantially the full length of the vessel, and the rear end is closed by an inclined plate 15 which is secured by welding or otherwise in a watertight manner, while the front end is similarly closed by inclined and converging plates 16, which plates may themselves be transparent, or, if desired, a window 17 of glass or other transparent material may extend thereacross so that the operator lying in a prone position may look ahead of the vessel therethrough to aid in navigating and "firing."

At the front end of the pilot's compartment is a periscope 18 which is adjustable in height in any well known manner and which is disposed conveniently with respect to the pilot's eye when the pilot is lying in prone position in the compartment, said periscope 18 being adapted for use in heavy seas or when navigating under conditions when vision through window 17 is not sufficient.

Access to the pilot's compartment is obtained

through a sliding hatch 19 at the top of the hood 14, which hatch is provided with means (not shown) to render the same substantially watertight to prevent the compartment from becoming flooded by heavy seas. On or adjacent the hatch 19 a pivoted air pipe 19a is provided which may be raised or lowered as desired, according to the severity of the weather, said air pipe 19a admitting air into the pilot's compartment when hatch 19 is necessarily closed, the angularity of air pipe 19a giving to the vessel the appearance of a limb of a log projecting from a partly submerged or water-soaked log, as the upper part of dome 14 would normally be painted or finished to resemble a water-soaked log. In good weather the hatch may be left open, or partly open, so he may rest better in a more or less sitting or upright position when enemy vessels are not near. In choppy weather the pilot may raise periscope 18 and air pipe 19a. At night or lying idle, the pilot may close the hatch 19 and raise pipe 19a to admit air, and the pilot may then sleep. Thus the pilot may remain away from the mother ship or base for several days, for within the pilot's compartment on the walls thereof are a plurality of shelves or racks 21 which may be conveniently used for storing articles of food, clothing, or other supplies; also for a medical kit, and for life belts, or other necessary articles.

A port hole 20 may also be provided at the top of hood 14, said port hole having a glazed frame which is so hinged that the same may be swung closed during stormy weather, or when open will permit air to enter the compartment in event the pilot's compartment becomes "stuffy." Port hole 20 may also be used for the purpose of upward vision by the pilot.

At the rear end of the lower hull portion are struts 22 in which a rudder 23 for the vessel is journaled, said rudder carrying a bevel gear 24 meshing with a bevel gear 25 on a steering shaft 26, which is disposed substantially axially of the vessel slightly above the floor 2 and extends adjacent an instrument panel 27 at the front of the pilot's compartment, which preferably extends to the sides of hood 14 and to the front plate 16 so as to enclose the turbine 31 and prevent excessive heat being radiated into the pilot's compartment, suitable sliding panels being provided thereto to admit a regulated amount of heat whenever desired. Panel 27 has a steering wheel 28 thereon operating steering shaft 26 through intermeshing bevel gears 29 and 30 rotation of handwheel 28 effecting steering of the vessel on any desired course. On the instrument panel 27 or adjacent thereto may be mounted the various air, steam, water and oil gauges, also any necessary or customary navigating instruments.

The vessel may be propelled by compressed air, but in the embodiment shown the vessel is steam propelled, utilizing a small steam turbine 31 disposed at the front end of the pilot's compartment driving a propeller shaft 32 disposed on the axis of the vessel, which shaft 32 passes down through a stuffing box 33 in floor 2 and extends through oil tank C and out through a stuffing box 33 in the rear end plate 7 of the hull portion, said shaft 32 carrying a propeller 34 on its rear end. Turbine 31 is driven directly by steam from a boiler 35 conducted through pipe 36 having a readily accessible throttle valve 36a disposed at the front end of the pilot's compartment.

Boiler 35 is housed in a compartment E at the

rear end of the pilot's compartment, same being formed by a front partition 37 open at its lower end to permit access to the compartment and to permit air to enter the boiler compartment E from the larger pilot's compartment so as to support combustion at the burner 38 disposed beneath the boiler 35, the fuel from tank C to the burner 38 being controlled by a rod 39 journaled in brackets on the floor 2 and having a hand-wheel 40 or the like at its front end which is readily accessible to the pilot. If desired the partition 37 may be provided with slide panels in its upper portion to permit regulation of heat from compartment E passing into the pilot's compartment when the turbine 31 was not running and during cold weather. The customary regulators now in common use may be used to regulate the oil supply from oil tank C to the burner 38 by means of steam pressure. The heat and fumes from the burner 38, also any smoke arising from improper adjustment of the burner fuel supply, will be confined in hood 35a surrounding the boiler 35, the upper end of which hood is contracted as at 35b and registers with a pivoted smoke pipe 35c adjustably arranged similarly to air pipe 19a. If burner 38 is properly adjusted there would be no appreciable amount of smoke generated. Also, the top of hood 14 directly over the boiler 35 may be made of light material, so that in event of explosion little damage would be done to the pilot or adjacent parts.

The water level in boiler 35 may be automatically controlled as is common practice, the water being supplied from water tank D, and the pressure in water tank D being maintained higher than the boiler pressure by means of a hand pump, or by means of an air pump hereinafter described.

The rear end of the boiler compartment E is closed by a solid partition 41 opposite the upper end of the inclined end plate 15, and the space between the partition 41 and plate 15 and floor 2 forms a tank F for water of condensation, the level of water in tank F being maintained from the fresh water tank D in the hull section by a water pump, hereinafter described. The exhaust from turbine 31 passes through pipe 42 through the side of the hood 14 and along the side of the hood rearwardly to a point opposite the condensate tank F, at which point the pipe 42 enters the tank and extends vertically upwardly therein terminating at a point adjacent the upper end thereof. Water from tank F is pumped to boiler 35 by a water pump, hereinafter described, the water being preheated in passing through coils in the burner area as is common practice, and hence the coils need not be shown.

The exhaust pipe 42 of the turbine 31 is thus cooled by the sea water which assists in condensing the steam, the condensation being carried to the exhaust chamber F, thus conserving the fresh water for the boiler so that little steam, if any, escapes through the exhaust pipe 43 of compartment F, which pipe is vertically adjustable in the manner of pipes 19a and 35c to suit weather conditions. By this construction very little if any fresh water for steam purposes is lost and very little exhaust steam is emitted from the exhaust pipe 43 which would divulge the whereabouts of the vessel while maneuvering towards the enemy vessels. What little steam may be emitted could be directed downwardly below the sea level by swinging pipe 43 so that such steam would never be noticed.

On the propeller shaft 32 adjacent turbine 31 are a pair of floating clutch disks 44 and 45 cooperating with a splined clutch engaging member 46 actuated through suitable linkage by a clutch lever 47 pivoted on the instrument panel 27, whereby when the clutch lever 47 is pushed forwardly the clutch disk 45 will be rotated by the propeller shaft, and when the clutch lever 47 is pulled rearwardly the clutch disk 44 will be rotated by said shaft.

Clutch disk 44 drives, by belt or chain 48, an air pump 49 disposed in the front end of the pilot's compartment, and a pipe 50 extends from the outlet of pump 49 rearwardly to a T 51, one branch of the T having a pipe 52 which discharges downwardly into the top of ballast tank A, as shown in Fig. 5, a hand valve 53 being interposed in pipe 52. From the other branch of T 51 a pipe 54 extends, the same discharging downwardly into the top of the opposite ballast tank B, pipe 54 having a hand valve 55 interposed therein. By the above arrangement, when pump 49 is actuated air under pressure is forced into either or both ballast tanks A and B by manipulation of the valves 53 or 55.

In pipe 54 is a second T 56, and a pipe 57 extends therefrom and discharges downwardly into the fuel oil tank C on the longitudinal axis of the vessel, said pipe 57 having a valve 58 interposed therein so that when air pump 49 is operating with valve 58 open, oil from tank C will be forced to the steam or other regulator (not shown) which supplies and maintains the flow of fuel to the burner 38 of the boiler.

Sea water is admitted into the ballast tanks A and B through sea valves 59 extending through each side of the lower hull section, as shown in Figs. 2 and 5, said valves having actuating levers, 60 controlled by links 61 which pass through the tanks A and B and are connected to one of the legs of bell crank levers 62, which levers 62 are journaled on the plate 2 in convenient reach of the pilot, one leg of each bell crank lever forming the handle disposed above the plate 2, and the other leg being connected with the arm 61 below said plate 2. By the above construction either of the tanks A or B may be flooded with sea water by manipulating the respective bell crank lever 62 to open the related sea valve 59, while the other sea valve may remain closed. Also, either ballast tank A or B may be subjected to air pressure, by manipulating the respective hand valves 53 or 55 when air pump 49 is in operation.

In order to control the trim or ballast of the vessel, after one of the torpedoes T has been discharged, it may be desirable or necessary to transfer sea water from one ballast tank such as A to the opposite tank B, or vice versa, and for this purpose a transverse pipe 63 is provided at the lower rear end of the hull section exteriorly of the hull, the ends of the pipe connecting the ballast tanks A and B as more clearly shown in Figs. 2 and 4. In pipe 63 is a valve 64 operated by a rod carrying an arm 65 which is actuated by a link 66 extending through a stuffing box 67 in the rear plate 15 of the pilot's compartment, link 66 extending forwardly to a position convenient to the pilot and being secured to one arm of a bell-crank lever 66a (Fig. 2) whereby actuation of the lever 66a will open valve 64 to permit sea water to be forced under the action of compressed air from one ballast tank such as A into the other tank B, or vice versa, when both of the sea valves 59 are closed

and one of the hand air valves 53 or 55 are open, the transferred sea water thus correcting the trim or ballast of the vessel, compensating for the loss of weight at one side of the vessel due to "fling" of one of the torpedoes T. Also by manipulating the sea valves 59 and the air valves 53, 55, the degree of submergence of the vessel may also be controlled by regulating the amount of ballast water in the respective tanks A and B.

10 The particular form and arrangement of piping and valving shown in the drawings is merely conventional, and any desired types of valves and operating means may be used.

Clutch disk 45 drives, by belt or chain 68, a water pump 69 which draws fresh water through intake pipe 70 extending down into fresh water tank D, of the lower hull section, and pumps the water through pipe 71 to the boiler 35, which water may be preheated by means of the usual water coils in the area of the burner 38 as is common practice, and therefore such coils are not shown in the drawings; also fresh water pipe 71 may have a faucet disposed at a convenient position in the pilot's compartment 25 whereby water for drinking and other purposes is readily available. Said pump 69 is piped to lowest point in pilot's compartment to act as a bailer of leaking water.

In order to prevent accidental explosion of the 30 torpedoes T in their respective tubes 1, due to accidental contact of their percussion caps with floating objects, such as logs or debris, gate frames 72 (Fig. 3) are provided, same being of somewhat larger area than the front ends of tubes 1, said frames 72 being hinged as at 73 to the front plates 6 of the lower hull section so as to be swingable vertically to permit the respective torpedo to pass out of its tube 1, but said frames 72 when lowered closing the front ends of the 35 tubes. Preferably frames 72 are covered with heavy wire mesh 74 or the like, which mesh preferably carries solid plates 75 at their centers for purposes of reinforcement, said plates 75 being disposed opposite but spaced from the percussion caps of the torpedoes T. Since the frames 72 are covered for the most part with wire mesh, sea water may readily pass into the tubes 1 so that the torpedoes will be immersed in the sea water at all times when the vessel is in the water.

50 In order to raise the gate frames 72, cables 76 or the like are provided having their lower ends secured to eyes 77 at the lower portions of the frames, said cables passing upwardly and entering an aperture 78 at the top front end of the 55 pilot's compartment, said cables extending down through said aperture 78 and having their lower ends knotted so as to prevent the cables from passing upwardly through said aperture. By the above construction, when a torpedo T is to be 60 released or "fired," the knotted end of the related cable 76 is grasped and pulled by the pilot lying in a prone position in the pilot's compartment, thereby raising the related frame 72 out of the path of the torpedo. After the torpedo has 65 cleared the tube the cable may be released to permit frame 72 to again fall back into normal position.

Operation

The vessel above described may be readily based 70 on a mother ship or some transporting means, and when approaching the path of enemy vessels same may be readily launched from such ship or base with the pilot in his compartment and torpedoes placed in each of the tubes 1, which 75 torpedoes are positioned in the tubes as herein-

above described, the same being confined by the lugs 1a, 1b and the screws 8, which screws 8 prevent chattering of the torpedoes in the tubes; and the torpedo propelling mechanism being in contact with the actuating screw 11, as shown in Fig. 1. The gate frames 12 are at the time of launching in lowered or closed position shown in Fig. 3.

The tanks A, B, C, D, are then placed in proper condition for ballast, and with respect to pressures, so that water will be supplied to fill and maintain the boiler with the proper level of fresh water, and to supply fuel oil to the burner.

Before placing the torpedoes in the tubes 1, their respective rudders are set for a "straight" course. When thus launched the pilot may maneuver the vessel under its own power to the proper or desired location, the vessel having such cruising range that the pilot may lurk or lay in wait for the enemy unsuspectedly for several days time. Upon seeing the enemy vessels approach he may maneuver the vessel close to such course and wait until the enemy vessels are well within range for accuracy, the vessel lying nearly entirely submerged in the water, giving same the appearance of an inoffensive water-soaked log floating partly submerged, the pipes 19a, 35c and 43 together with the periscope having the general appearance of limbs of such log, the same being normally disposed at different angularities with respect to the axis of the vessel. While lying in wait, and while maneuvering into position, no noise is emitted from the vessel which a sound-device could pick up; and thus the pilot has the opportunity of maneuvering within very close range of the enemy vessels.

At the proper time the operator starts the turbine in order merely to aim the vessel so that the torpedoes will be launched in the proper direction, and at the same time he may still maneuver a little closer to the approaching enemy vessels. When ready to "fire," the pilot raises the related frame 12 of one of the torpedoes and then backs the screw 8 out of contact with the torpedo and manipulates the related hand wheel 13, setting the torpedoes propelling mechanism into action, whereupon the torpedo is noiselessly propelled under its own power out of the front end of the tube 1, and is sped on its course. If other torpedoes are necessary, he repeats the above procedure for such torpedoes.

After firing the first torpedo, however, the vessel may assume an uncomfortable list, due to unbalanced weights, but the pilot may readily rectify this condition by either opening the sea valve 59 at the higher side of the vessel, i. e., that from which the first torpedo was fired, to permit sea water to flow into the related ballast tank A or B, and thus restore the trim or ballast of the ship, such procedure maintaining the degree of submergence of the vessel in the water; or he may open the valve 64, both sea valves 59 being closed, and inject air under pressure into the ballast tank A or B which is then at the lower side of the vessel, and thereby blow ballast water from the lower tank A or B into the higher tank B or A and thus restore the trim, equilibrium, or ballast of the vessel. After the torpedoes have been discharged, the pilot may then unsuspectedly maneuver the vessel back to its mother ship or base without appreciable noise, since the turbine exhaust pipe 43 may be lowered to discharge any exhaust steam below the surface of the water.

My novel one-man torpedo boat may thus be maneuvered by the pilot stealthily and unnoticed

into position to fire torpedoes at close range; also same may be built quickly in small shops not otherwise equipped for heavy marine construction; and same may be built at low cost since same involve the use of no complicated machinery such as internal combustion engines or heavy batteries; also the same may be based or carried on small vessels, owing to its light weight; and may be operated at minimum expense.

Fig. 6 shows diagrammatically a modification utilizing four torpedo tubes in the hull instead of only two as shown in Figs. 1 to 5. A similar arrangement of valving and piping and fresh water, ballast water, and fuel oil tanks in the hull section would be used as previously described, and the four torpedo tubes 1 would extend throughout the entire length of the hull section. Where four torpedo tubes 1 are used, it may be possible to discharge or "fire" the torpedoes from either or both of the two inner tubes 1 without materially disturbing the ballast or trim of the boat.

In this modification (Fig. 6) the upper portion of hood 14 of the pilot's compartment is preferably of same width as the upper portion of the hood in Figs. 1 to 5. However, the lower portion of the hood 14 may be conveniently flanged outwardly as at 14a and extended to meet the sides of the lower hull section. The space between the top of the hull section and the wings 14a of the hood 14 may provide convenient storage spaces for the reception of food, clothing, bedding and other stores. Since the upper portion of the hood 14 is of same width as that shown in Figs. 1 to 5, the appearance of the partially submerged boat in the water would also be that of a water-soaked log. If the upper portion of the hood 14 however were widened to conform with the increased width of the lower hull section, the width of the exposed portion of the hood would obviously be too great to impart thereto the appearance of a floating log.

The spaces between the top of the lower hull portion and the wings 14a might, if desired, form additional ballast tanks so that, when filled with water, the torpedo boat would be capable of total submergence in cases of emergency for a short time, such as at the moment of "firing" the torpedoes, or immediately thereafter, when the enemy would most likely be ardently searching for the torpedo boat.

In either modification, a section of one of the tanks in the hull section could be utilized for compressed air supplied by the air pump 49, to provide more air space than would be available over the oil in the oil tanks when the latter contained large amounts of oil.

My novel torpedo boat permits the use of smaller and less expensive torpedoes, due to the fact that the torpedoes need not contain as large a supply of oil, water and air as normally, in order to propel itself relatively short distances between the torpedo boat and the targets. Standard torpedoes are customarily released about five miles from their targets, and if the torpedoes should miss the targets same generally proceed under their own power for a distance of eight miles, more or less, beyond the targets, thus giving a range of approximately thirteen miles for the standard torpedo, the torpedo finally sinking itself after missing the target. My torpedo boat permits utilization of torpedoes carrying explosives equal in strength to those of standard torpedoes, but as same are released or "fired" at distances ranging from only one-half to one mile,

instead of five miles, from the target, the torpedoes may be reduced to approximately 15' in length as compared with the standard torpedoes of approximately 26' length. Moreover, the torpedoes used in my torpedo boat may have a 12 to 16" diameter as compared to the normal 21" diameter of the standard torpedo. Thus my torpedo boat may be utilized to fire torpedoes costing approximately half that of the standard torpedoes, while carrying the same explosive charge.

I do not limit my invention to the exact forms shown in the drawings, for obviously changes may be made therein within the scope of the claims.

I claim:

1. A torpedo boat, comprising a hollow submersible hull portion having top, bottom, sides, and ends; a torpedo tube therein opening through the said ends of the hull, said hull being of length greater than a self-propelled torpedo; ballast tanks in the hull at opposite sides of the tube; a fluid-tight hood secured upon the hull portion forming a partly submersible pilot's compartment; means operable from said compartment for propelling and steering the boat; means in said tube for respectively holding a torpedo inserted therein; means operable from the compartment for starting the torpedo for self-propulsion through the front end of the tube; and means for admitting sea water into and ejecting sea water from the respective ballast tanks.

2. In a torpedo boat as set forth in claim 1, said hood being relatively low to cover the pilot lying in a prone position thereunder; and a watertight hatch in the top of the hood permitting access to said compartment.

3. In a torpedo boat as set forth in claim 1, said means for admitting and ejecting sea water, comprising sea valves in the sides of the hull portion having controls extending into the compartment; and pressure means for forcing the water outwardly through the open sea valves.

4. In a torpedo boat as set forth in claim 1, said propelling means including a prime mover, a propeller shaft operated thereby; and said means for admitting and ejecting sea water comprising sea valves in the sides of the hull portion having controls extending into the compartment; an air pump in the compartment clutched to said shaft; and valved pipes extending from the air pump and discharging into the said ballast tanks.

5. In a torpedo boat as set forth in claim 1, said torpedo holding means comprising spaced lugs as the rear end of the tube adapted to straddle the torpedo fins; other lugs contacting the rear ends of said fins; and a retractable screw operable from the compartment adapted to enter the tube and press the front end of the torpedo down in said tube.

6. In a torpedo boat as set forth in claim 1, said torpedo starting mechanism comprising a member operable from the compartment entering the tube and engaging the self-propelling devices of the torpedo therein; said member being retractable to permit the torpedo to emerge from said tube.

7. In combination with a torpedo boat as set forth in claim 1, a perforated gate at the front end of the tube, and means operable from the compartment for shifting the gate to permit the torpedo to emerge from the tube.

8. A torpedo boat comprising a hollow submersible hull portion of substantially rectangular cross section and having closed ends; a

plurality of spaced torpedo tubes therein disposed in parallel spaced relation and opening through the ends of the hull, said hull being of length somewhat greater than a self-propelled torpedo; the outermost tubes closing off spaces between the tubes and sides of the hull to form separate starboard and larboard ballast tanks; a hood secured upon the hull portion forming a partly submersible pilot's compartment; means operable from said compartment for propelling and steering the boat; means in each of said tubes for respectively holding a torpedo inserted therein; means operable from the compartment for starting the torpedoes for self-propulsion through the front ends of their related tubes; means for admitting sea water into and permitting ejection of sea water from the respective ballast tanks; means for forcing compressed air into the respective ballast tanks; and means for transferring ballast water from one ballast tank to the other.

9. In a torpedo boat as set forth in claim 8, said boat being steam propelled and having a boiler and turbine in the pilot's compartment; and division plates between adjacent tubes dividing the space between adjacent tubes into separate upper and lower fuel and fresh water tanks.

10. In a torpedo boat as set forth in claim 8, said hood being semi-cylindrical and relatively low to cover the pilot lying thereunder in a prone position; and a water-tight hatch in the top of the hood permitting access to said compartment.

11. In a torpedo boat as set forth in claim 8, said means for admitting and permitting ejection of sea water comprising sea valves in the sides of the hull portion having controls extending into the compartment.

12. In a torpedo boat as set forth in claim 8, said propelling means including a prime mover, a propeller shaft operated thereby; and said compressed air admitting means comprising an air pump clutched to said shaft, and valved pipes extending from the air pump and discharging into the said ballast tanks.

13. In a torpedo boat as set forth in claim 8, said transferring means comprising a pipe connecting the ballast tanks at each side of the hull portion, and a valve in said pipe controlled from the pilot's compartment.

14. In a torpedo boat as set forth in claim 8, said torpedo holding means comprising spaced lugs at the rear ends of the tubes adapted to receive therebetween the torpedo fins, other lugs contacting the rear ends of the torpedo fins; and retractable screws operable from the compartment adapted to enter the tubes and press the front ends of the torpedoes down in their tubes.

15. In a torpedo boat as set forth in claim 8, said torpedo starting mechanism comprising members operable from the compartment and entering the tubes and engaging the self-propelling devices of the torpedoes, said members being retractable out of the tubes to permit the torpedoes to emerge from the tubes.

16. In combination with a torpedo boat as set forth in claim 8, perforated gates at the front ends of the tubes, and means operable from the compartment for shifting the gates to permit the torpedoes to emerge from the tubes.

17. In a torpedo boat, an open-ended submerged torpedo tube, spaced lugs adjacent the rear end of the tube adapted to receive therebetween the torpedo fins, other lugs within the tube contacting the rear ends of the torpedo

fins; and a retractable screw adapted to enter the tube and press the front end of the torpedo therein down in the tube.

18. In combination with a torpedo boat as set forth in claim 17, torpedo starting mechanism comprising a member entering the tube and engaging the self-propulsion control device of the torpedo, said member being retractable out of

the tube to permit the torpedo to emerge from the tube.

19. In combination with a torpedo boat as set forth in claim 17, a perforated gate at the front end of the tube, and means for shifting the gate to permit the torpedo to emerge from the tube.
